200,187

COMBINED SHOWER HEAD AND BATH OIL DISPENSER

John E. Davis, Sherman Oaks, Calif., assignor to J. Briskin, Inc., Sherman Oaks, Calif., a corporation of California

Filed Dec. 27, 1963, Ser. No. 77,940

Term of patent 14 years

I claim:

The ornamental design for a combined shower head and bath oil dispenser, substantially as shown.
